DESIGN FOR A SLIDE BUCKLE

Rudolph E. Schreiber, Chicago, Ill.

Application November 22, 1943, Serial No. 111,758

Term of patent 14 years

To all whom it may concern:

Be it known that I, Rudolph E. Schreiber, a citizen of the United States, residing at Chicago, in the county of Cook and State of Illinois, have invented a new, original, and ornamental Design for a Slide Buckle, of which the following is a specification, reference being had to the accompanying drawing, forming a part thereof, in which:

Fig. 1 is a front elevational view of the slide buckle showing my new design.

Fig. 2 is an end elevational view thereof.
Fig. 3 is a plan view thereof.
Fig. 4 is a rear elevational view thereof.
Fig. 5 is an enlarged sectional view thereof, taken on line 5—5 of Fig. 1.

I claim:

The ornamental design for a slide buckle, substantially as shown.

RUDOLPH E. SCHREIBER.
